Primary Examiner — Karen S Acker*(74) Attorney, Agent, or Firm* — Fross Zelnick Lehrman & Zissu, P.C.; Charles T. J. Weigell, Esq.(57) CLAIM

The ornamental design for a fabric sheet material, as shown and described.

DESCRIPTION

The sole FIGURE is a front view of a fabric sheet material showing my new design.

The broken lines surrounding the drawing depict the boundaries of the claim and form no part thereof.

The fabric sheet material is intended to be applied to such goods as apparel, fabric piece goods and fabric bags as containers.
